UNITED STATES PATENT OFFICE.

EDGAR E. ROWE, OF CHICAGO, ILLINOIS, ASSIGNOR TO UNITED SHOE MACHINERY CORPORATION, OF PATERSON, NEW JERSEY, A CORPORATION OF NEW JERSEY.

TACKING MECHANISM.

1,399,799.

Specification of Letters Patent. Patented Dec. 13, 1921.

Application filed April 30, 1918. Serial No. 231,616.

To all whom it may concern:

Be it known that I, EDGAR E. Rowe, a citizen of the United States, residing at Chicago, in the county of Cook and State 5 of Illinois, have invented certain Improvements in Tacking Mechanisms, of which the following description, in connection with the accompanying drawings, is a specification, like reference characters on the drawings indicating like parts in the several figures.

This invention relates to tacking mechanism, and is herein shown, for purposes of illustration, as embodied in mechanism particularly adapted for use in the manufacture 15 of boots and shoes for securing portions of the shoe in proper relation. More particularly, the invention is herein illustrated in its application to a machine for pulling uppers over lasts, the illustrative machine having features of construction which are of particular utility in operation upon turn shoes. It will be understood, however, that the invention in its broader aspects, although 20 involving important advantages in use on turn shoe work as will be hereinafter explained, is not thus limited in utility nor restricted in its applicability to machines of the particular class exemplified by the construction shown.

30 Pulling-over machines of a well known type in common use comprise, in their organization, grippers which are operated to pull the upper over the last, and tacking mechanisms which are moved inward over the bottom of the shoe and are operated to drive a plurality of tacks at separated points for securing the upper in its pulled-over position. On McKay shoe work these tacks are fully driven, while on welt work and turn work 35 the tacks are only partially driven, a substantial portion of the tack being left projecting from the shoe to facilitate subsequent removal. On welt work it is the practice to drive the tacks through the upper and the 40 innersole and a substantial distance into the last in order to insure that the tacks shall securely hold the upper. In the manufacture 45 of turn shoes, however, and particularly of shoes of the better grades, it is undesirable 50 to drive the tacks entirely through the sole, since if this is done discoloration due to the chemical action of the sole leather upon the tacks is produced on the grain side of the sole and is visible in the finished shoe. The

thickness of the turn shoe sole, as compared 55 with the welt shoe innersole, provides sufficient substance for anchoring the tacks securely enough to hold the upper, and therefore affords opportunity for driving the tacks only partially through the sole in 60 such manner as to avoid marks on the finished side of the sole. Attempts to drive the upper fastening tacks in this manner have, however, heretofore met with serious 65 difficulties which it is one of the important objects of this invention to avoid.

Tacking mechanism of a well known type in use on pulling-over and other machines 70 comprises a tack holder having relatively separable portions provided in their adjacent faces with co-operating recesses which form a tack pocket for receiving and holding a tack, the two portions being normally held together under spring pressure, and a driver 75 which engages the tack in the pocket and forces it into the work. This mechanism is moved transversely of the edge of the shoe bottom into tack driving position, and after the tack is driven is moved reversely away from the tack. In order to insure effective 80 control of the tack in its passage from the tack holder to the work to cause it to be driven in the desired direction, it is necessary that the tack holder stand when in driving position, at a distance from the work 85 which is considerably less than the length of the tack. Consequently on turn shoe work, if the tack is driven only into the sole without piercing that surface of the sole which is next to the last, it is practically unavoidable, if 90 the tack is to be guided properly, that a portion of the tack shall be left projecting within the tack holder at the end of the driving movement of the tack driver. Under such 95 conditions it has been found that when the tacking mechanism backs away from the tack the tack holder, by engagement with the head of the tack partially confined within the tack pocket, tends to pull the tack laterally and in view of the relatively yieldable character of the sole material may bend it out of 100 its place or even withdraw it entirely from the shoe.

This invention provides an improvement in tacking mechanism whereby it is rendered 105 feasible to drive a tack only to the extent desired without involving any substantial danger of displacement of the tack in the

relative separating movement of parts of the mechanism and the work, however yieldable may be the character of the material into which the tack is driven. For the purposes in view the invention provides a construction in the operation of which an outlet passage such as to prevent displacement of the tack is afforded for that portion of the tack which remains within the tack holder at 10 the end of the tack driving operation. It is an important characteristic of the construction wherein the invention is herein shown as embodied that the portions of the tack holder are separated sufficiently in the 15 driving operation to relieve that portion of the tack which remains within the holder substantially from the pressure of the holder, and to afford a free outlet passage for the head of the tack, and are held in such condition until the holder has been withdrawn 20 from the tack.

The novel features of the invention, including certain details of construction and combinations of parts, will now be described 25 with reference to the accompanying drawings and pointed out in the claims.

In the drawings,

Figure 1 is a view in front elevation, with parts shown in section, of a portion of a 30 pulling-over machine having tacking mechanism in which the invention is embodied;

Fig. 2 is a view in perspective of a portion of the mechanism shown in Fig. 1, illustrating the relation of the parts to the shoe when 35 the tacking mechanism is in tack driving position;

Fig. 3 is a view similar to Fig. 2 illustrating the relation of the different parts to one 40 another and to the work after the tack has been driven and the tacking mechanism has been partially withdrawn;

Fig. 4 is a view showing the tack holder in vertical section and illustrating the position 45 of the tack prior to the tack driving operation,

Fig. 5 is a view similar to Fig. 4 illustrating the relative positions of the parts when 50 the tack driver is at the end of its driving movement, and

Fig. 6 is a perspective view of one of the 55 parts of the tack holder, illustrating the character of the tack receiving recess.

The invention is herein shown in its application to a pulling-over machine of a 60 well-known type particularly adapted for operation upon turn shoes and comprising, in addition to the upper pulling means, mechanism for working the forepart of the shoe upper into lasted position, the construction of the illustrative type of machine being more fully shown and described in a United States Letters Patent No. 1,280,613, granted on Oct. 1, 1918, upon an application of Orrell Ashton. The drawings show only a 65 portion of the pulling-over, lasting and tack-

ing means arranged to operate at one side of the forepart of the shoe, but it will be understood that the machine is provided with means for pulling the upper at the toe and at opposite sides of the forepart, means for wiping the upper into lasted position about the toe and along the opposite sides of the toe portion, and means for driving a plurality of tacks at each side of the shoe and also around the toe end of the shoe for holding 75 the margin of the upper in place.

In Fig. 1 is shown a portion of the sole rest 2 of the machine which engages the sole *a* of the shoe on the last *b* to hold the shoe against the strain of the upper pulling 80 means and determine the position of the plane of the sole relatively to the tacking means, one of the several grippers 4 which are operated to pull the upper *c* over the last, a portion of the lasting wipers 6 which are operated to wipe the upper over the sole around the toe, and one of the supporting and clamping devices 8 which engage the shoe at the opposite sides of the forepart to hold it and support it during the tacking 85 operation and to assist in positioning it relatively to the tacking means. In Fig. 1 is shown also one of the side tacker arms 10 of the machine which is mounted on a support 12 for swinging movement toward and from the shoe and carries a plurality of tack holders, comprising opposed fingers 14, and tack drivers 16, only one such holder and driver, however, being shown in the drawings. It will be understood that the machine is provided with another tacker arm 100 with its tacking mechanism at the opposite side of the shoe and with similar tacking mechanism for the toe end of the shoe. Since these different mechanisms, and the 105 different tack holders and drivers of each mechanism, involve no essential differences one from another as far as the embodiment of the present invention is concerned, it will be sufficient for an understanding of the invention to refer in detail only to one of the tack holders and its associated driver.

Connected to the driver 16 is a driver bar 18 which is mounted for lengthwise movement in the tacker arm 10 and receives its operative movement from an oscillatory driver arm 20 under the impulse of a spring 22. The driver bar 18 is normally upheld against the pressure of the spring operated arm 20 by the usual mechanism characteristic of machines of the illustrative type, and is released at the proper time in the cycle of operations of the machine to render the spring effective to impart operative movement to the bar to cause the driver 16 125 to drive the tack, the limit of driving movement of the bar and the driver being determined by the engagement of an adjustable washer 24 on the driver bar with a portion 130 of the support 12. The position of the

washer 24 and the limit of operative movement of the bar is determined by the adjustment of nuts 26 on the end of the bar. The movements of the tacker arm 10 and the mechanism carried thereby in directions toward and from the shoe are effected by means of a rack bar 28 and a gear segment 30, shown fragmentarily in Fig. 1, the construction and operation of this mechanism 5 and also of the means for effecting and controlling the operation of the driver bar being more fully shown and described in United States Letters Patent No. 1,082,487, granted on December 30, 1913 upon an application of Arthur Bates.

The tack holder, as more fully described in the prior patent of Orrell Ashton hereinbefore referred to, comprises the two complementary fingers 14 embracing and seated 10 in grooves in a supporting plate 32 on the tacker arm 10 and normally pressed together and held in place by means of a spring 34. The two fingers at their front ends are provided with complementary 15 grooves or recesses 36 which provide a pocket for the reception of the tack *d* deposited therein automatically at a predetermined time in the cycle of operations of the machine. Subsequent to the upper pulling 20 operation the tacker arm 10 is swung inward by its operating mechanism, in unison with the overdraw movement of the side gripper 4, into position for driving the tack, the inward movement of the tacker 25 arm being limited by engagement of a portion of the mechanism carried thereby with a part of the side clamp mechanism 8. During the latter portion of the inward movement of the tacker arm the gripper 30 is tripped and caused to release the margin of the upper, and after the tacking mechanism has arrived at its limit of inward movement, the driver bar 18 is released to the action of the spring arm 20 35 to cause the tack to be driven. While the driver 16 is held substantially at the end of its driving movement, the tacker arm 10 is swung outward to carry the tack holder clear of the tack and continuing its movement is returned to its starting position, the 40 driver bar 18 being then raised to withdraw the driver from the tack pocket and leave the pocket in condition for the reception of another tack.

For the purposes of this invention each 45 of the recesses or grooves 36 in the adjacent sides of the tack holder fingers 14 is provided at its lower end with a tapering portion 40 of considerable length, these tapering portions coöperating to provide a comparatively narrow tapered recess for guiding the tack. As the tack is forced outward by the action of the driver 16, the shank of the tack is forced through this narrow recess 50 which serves as a guide to insure that

the tack shall be driven in the right direction, causing the two fingers to separate slightly against the tension of the spring 34, the two fingers being further separated by the wedging action of the head of the tack and then of the end of the driver 16 on the walls of the tapered recess near the end of the tack driving operation. Preferably the tack holder is positioned in sufficiently close proximity to the work to permit a substantial portion of the length of the tack to be forced into the work before the driver becomes effective to spread the fingers 14. The tack is thus held in effective control as to the direction of its driving movement during its passage between the tack holder and the work and until it has effected a substantial entrance into the work. As the head of the tack is forced downward through the tapered recess at the lower end 55 of the tack pocket the driver 16, which is preferably of slightly larger diameter than the head of the tack, becomes effective upon the walls of the recess to wedge the walls apart during the continued driving movement of the tack. For the purposes of this invention, the movement of the driver 16 is limited by adjustment of the washer 24 to prevent the tack from being driven entirely through the sole *a*, and as shown in Fig. 5, which illustrates the positions of the parts at the end of the movement of the driver, the tack *d* is left with its head portion still projecting within the tapered recess of the tack holder. In this position, 60 however, as will be evident by reference to Fig. 5, the driver 16 is effective to hold the fingers 14 apart sufficiently to prevent clamping action of the fingers upon the head of the tack and to afford a free outlet passage for the head of the tack between the front portions of the fingers. As hereinbefore explained, the driver remains substantially at the limit of its driving movement until after the tacking mechanism has 65 been withdrawn laterally away from the tack, as illustrated by Fig. 3, although it will be evident that in the construction shown the driver, by its engagement with the walls of the tapered recess, will remain effective to prevent any substantial displacing action upon the tack even if the driver begins its return movement before the tack holder is entirely clear of the tack. It will 70 be evident that by the construction herein provided any such pressure of the parts of the tack holder upon the tack as would tend to displace the tack laterally is entirely obviated, and that however lightly the tack may be anchored in the work, there is no 75 danger of bending it or of withdrawing it from the work during the retractive movement of the tacking mechanism.

While the term "tack" is used herein to 80 designate the fastener which the illustrative

mechanism is adapted to drive, it will be evident that the invention is not limited in utility to mechanism for driving fasteners of the precise form shown, and it should therefore be understood that the term is used in a generic sense as applicable to various forms of fasteners.

Having described the invention, what I claim as new and desire to secure by Letters Patent of the United States is:

1. In mechanism for applying to shoes upper holding tacks which are to be subsequently pulled, the combination with means for determining the plane of the tack receiving surface of the shoe, of a tack holder between which and the shoe there is provision for relative movement toward and from tacking position transversely of the direction of driving movement of the tack, a tack driver, driver operating means and controlling means arranged to arrest the movement of said driver at such a distance from said plane as to leave a portion of the driven tack projecting outside of the tack receiving surface of the shoe, said holder being constructed and arranged to guide the tack beyond the limit of the movement of the driver and to be conditioned by the driver to present a free outlet passage for the head portion of the driven tack until the holder is clear of the tack in the relative movement of the shoe and the holder laterally of the tack away from the tacking position.
2. In mechanism for applying to shoes upper holding tacks which are to be subsequently pulled, the combination with means for determining the plane of the tack receiving surface of the shoe, of a tack holder between which and the shoe there is provision for relative movement toward and from tacking position transversely of the direction of driving movement of the tack, said holder comprising relatively separable portions constructed to position a tack between them, yieldable means for relatively positioning said portions of the holder while permitting their relative separation in the tack driving operation, a tack driver, driver operating means and controlling means arranged to arrest the movement of the driver at such a distance from said plane as to leave a portion of the driven tack projecting outside of the tack receiving surface of the shoe, the separable portions of said tack holder being constructed to guide the tack beyond the limit of the movement of the driver and to be wedged apart and held by the driver in such relation as to provide an outlet passage for the head portion of the driven tack of a width to prevent pressure on the sides of the head of the tack during the relative movement of the shoe and the holder to clear the holder from the tack.
3. In mechanism of the class described, a

tack holder comprising relatively separable portions constructed to position a tack between them, means for effecting relative movement of said holder and the work after the driving of a tack, and means for driving a tack only partially out of said holder and into the work and for effecting and maintaining such relative separation of the portions of the holder as to provide an outlet passage for the tack of a width to prevent any substantial pressure of the holder on the tack until the holder is clear of the tack in the relative movement of the holder and the work after the tack driving operation.

4. In mechanism of the class described, a tack holder comprising relatively separable portions constructed to position a tack between them, yieldable means for relatively positioning said portions of the holder while permitting their relative separation in the tack driving operation, tack driving means, means for controlling said driving means to cause a portion of the tack to be left upstanding from the work and within the tack holder at the end of the driving operation, and means for moving the tack holder laterally of the tack to withdraw said holder from the tack, the tack driving means and the tack holder being constructed to cooperate for maintaining such relative separation of the portions of the holder as to provide an outlet passage for the driven tack of a width greater than the diameter of the head of the tack to prevent displacement of the tack in the withdrawal of said holder.

5. In mechanism of the class described, a tack holder comprising relatively separable portions having opposed recesses for holding a tack, yieldable means for relatively forcing said portions of the holder toward each other while permitting their relative separation in the tack driving operation, a tack driver, means for operating said driver, and means for effecting relative movement of the holder and the work after the driving of a tack, said driver and operating means being constructed and arranged to force the tack only partially out of the holder and then to maintain the portions of the holder separated in such manner as to provide an outlet passage for the tack of a width to prevent any displacing action of the holder upon the tack until the holder is clear of the tack in the relative movement of the holder and the work.

6. In mechanism of the class described, a tack holder comprising relatively separable portions having opposed recesses for holding a tack, yieldable means for relatively positioning said portions of the holder while permitting their relative separation in the tack driving operation, a tack driver, means for operating said driver, means for limiting the movement of the driver to cause

the head portion of the tack to remain between the two portions of the tack holder at the end of the driving operation, and means for effecting relative movement of the 5 holder and the work after the driving of a tack, said driver and the walls of said recesses being constructed and arranged to cause the driver to effect such relative separation of the portions of the holder as to 10 provide an outlet passage for the tack of greater width than the diameter of the head of the tack and to maintain the portions of the holder thus separated to prevent displacing action of the holder upon the tack until 15 the holder is clear of the tack in the relative movement of the holder and the work after the tack driving operation.

7. In mechanism of the class described, a tack holder comprising relatively separable 20 portions constructed to position a tack between them, a tack driver, means for operating said driver, means for limiting the movement of the driver to cause the head portion of the tack to remain within the 25 holder at the end of the driving operation, and means for effecting relative movement of the holder and the work after the driving of a tack, said portions of the holder having elongated tapering recesses opposed to each 30 other for holding and guiding the tack, and the driver and the walls of said recesses being constructed and arranged to cause the driver to effect a relative separation of the two portions of the holder and to maintain 35 said portions in such separated relation as to provide an outlet passage for the tack of a width to prevent any displacing action of the holder upon the tack during the relative movement of the work and the holder 40 to clear the holder from the tack.

8. In mechanism of the class described, a tack holder comprising relatively separable portions having opposed recesses with tapered walls for holding and guiding a 45 tack, yieldable means for relatively forcing said portions of the holder toward each other while permitting their relative separation in the tack driving operation, a tack driver, means for operating said driver to 50 force the tack into the work and to effect by engagement with the walls of said recesses a relative separation of the portions of the holder, means for limiting the movement of the driver to cause the head portion of the 55 tack to remain within the tack holder at the end of the driving operation, and means for effecting relative movement of the holder and the work after the driving of a tack, said driver being larger in cross section than 60 the head of the tack and so controlled as to cause the driver at the end of its driving movement to separate the portions of the holder sufficiently to provide a free outlet 65 passage for the tack and to maintain such separation until the holder is clear of the

tack in the relative movement of the holder and the work after the tack driving operation.

9. In mechanism of the class described, a tack holder comprising relatively separable 70 portions constructed to position a tack between them, tack driving means, and means for moving the tack holder laterally of the tack to withdraw it from the tack after the driving operation, said driving means being 75 so constructed and operated as to force the tack only partially out of the holder in the driving operation and to maintain the portions of the holder separated sufficiently to provide an outlet passage for the tack of 80 such width as to prevent any displacing action of the holder upon the tack during the withdrawing movement of the holder.

10. In mechanism of the class described, a tack holder comprising relatively separable 85 portions having opposed recesses for holding a tack, yieldable means for relatively forcing said portions of the holder toward each other while permitting their relative separation in the tack driving operation, a 90 tack driver, means for operating said driver, means for limiting the movement of the driver to cause the head portion of the tack to remain between the two portions of the holder at the end of the driving operation, 95 and means for moving the tack holder laterally of the tack to withdraw it from the tack after the driving operation and while the driver is substantially at the end of its driving movement, said driver and the walls 100 of said recesses being constructed and arranged to cause the driver to effect and maintain such relative separation of the portions of the holder as to provide a free outlet 105 passage for the tack until the holder is clear of the tack.

11. In mechanism of the class described, a tack holder comprising relatively separable portions having opposed recesses with tapered walls for holding and guiding a tack, 110 yieldable means for relatively forcing said portions of the holder toward each other while permitting their relative separation in the tack driving operation, a tack driver, means for operating said driver to force the tack into the work and to effect by engagement with the walls of said recesses a relative separation of the portions of the holder, means for limiting the movement of the driver to cause the head portion of the 115 tack to remain within the tack holder at the end of the driving operation, and means for moving the tack holder laterally of the tack to withdraw it from the tack after the driving operation and while the driver is substantially at the end of its driving movement, said driver being larger in cross section than the head of the tack to cause the 120 driver to maintain such relative separation of the portions of the holder as to provide 125 a free outlet passage for the tack until the holder is clear of the tack.

a free outlet passage for the head of the tack until the holder is clear of the tack.

12. In mechanism for securing the upper of a turn shoe in pulled-over position, the combination with shoe positioning means, of a tack holder movable transversely of the edge of the shoe bottom into and out of position for the driving of a tack, said holder comprising relatively separable portions constructed to position a tack between them, a tack driver, means for operating said driver, and means for limiting the movement of the driver to cause the tack to be driven only partly through the sole of the shoe with a portion of the tack left upstanding from the work and within the tack holder, said driver and holder being constructed and arranged to cause the driver to maintain such relative separation of the portions of the holder as to provide an outlet passage for the tack of a width to prevent any displacing action of the holder on the tack during the movement of the holder to clear the tack.

13. In tacking mechanism, the combination with work positioning means, of a tack holder comprising relatively separable parts for holding and guiding a tack, a tack driver, means for operating said driver to drive a tack only partially out of the holder and into the work, and means for effecting relative movement between the work and said tack holder and driver laterally of the tack to clear the tack from the holder when the driver is substantially at the end of its driving movement, the parts of said tack holder having walls with tapering inner faces elongated lengthwise of the driver to be wedged apart by the driver and formed to coöperate with the driver to provide a free outlet between the parts of the holder for the head of the tack in said relative movement to clear the tack from the holder.

In testimony whereof I have signed my name to this specification.

EDGAR E. ROWE.
